GAME BOARD

Frank H. Cross, Baltimore, Md.

Application February 9, 1937, Serial No. 124,915

1 Claim. (Cl. 273—139)

This invention relates to game boards of a type wherein a plurality of removable sections are assembled to make up the complete board, each of these sections being formed with a plurality of holes in which are contained slips of paper on which are printed names, numbers or other data to be used in playing the game.

An object of the invention is to provide a sectional board the different sections of which can be removed and others substituted if, when the game is played, a tie results which requires additional plays after the sections already in play have been exhausted.

A further object is to provide a game board the size of which can be enlarged or reduced, in proportion to the number of players using it.

A further object is to provide removable sections cooperating with baffles of peculiar configurations whereby only sections adapted for use in connection with the particular board, can be employed.

With the foregoing and other objects in view which will appear as the description proceeds, the invention consists of certain novel details of construction and combinations of parts hereinafter more fully described and pointed out in the claim, it being understood that changes may be made in the construction and arrangement of parts without departing from the spirit of the invention as claimed.

In the accompanying drawing the preferred form of the invention has been shown.

In said drawing

Figure 1 is a plan view of the game board.

Figure 2 is a section on line 2—2, Figure 1, the bottom plate being shown by broken lines in unlocked position.

Figure 3 is a section on line 3—3, Figure 1.

Figure 4 is a section on line 4—4, Figure 1.

Figure 5 is a plan view of one of the sections of the game board, a portion being broken away.

Referring to the figures by characters of reference 1 designates a top plate having downturned flanges forming sides 2 and an end wall 3. Channeled arms 4 are extended from one end of the plate in which can be inserted a card bearing instructions, advertising matter, or other data. For the purpose of preventing the plate from marring any surface on which it might be mounted, suitable soft pads 5 of any desired construction can be placed on the corner portions as shown.

Plate 1 is formed with parallel rows of windows or openings 6 preferably rectangular and these correspond with similar windows or openings 7 formed in a bottom plate 8 proportioned to be

inserted between the lower edges of the side walls or flanges 2 and against the end wall 3. This will be noted by referring to Figures 2 and 3. End wall 3 has a narrow lip or ledge extended backwardly therefrom as shown at 9 and this is adapted to be lapped by one end portion of plate 8 so as to support it. The opposite end of the bottom plate 8 has an upturned flange 10 formed with an opening 11. When this bottom plate is in normal position flange 10 bears against the bottom surface of the top plate 1 as shown by full lines in Figure 2 and when thus located the opening 11 can receive the bolt 12 of a lock 13 secured to plate 1. Therefore the plate 8, after once being fastened, cannot be removed except by actuating the lock so as to withdraw the bolt 12 from opening 11.

Secured to the bottom of plate 1 and extending around the group of openings 6 are baffles 14 which can be in the form of angle strips having flanges extended toward each other as shown at 15. These flanges can be made flat, as shown or angular, curved or of any other desired configuration.

Substantially filling the space surrounded by the baffle strips 14 are parallel rows of game board sections 16 adapted to abut against each other at their edges, the meeting edges being concealed between those portions of the plates 1 and 8 left between the openings in the plates. This will be apparent by referring to Figures 2 and 3. Grooves 17 are provided in the sides and ends of the board sections and are so shaped and proportioned that those game sections located nearest the baffles 14, can receive the flanges 15 of the baffles as shown. Thus it will be obvious that unless the game board sections have their grooves shaped to fit the baffles, it would be impossible to place all of the game board sections in the space provided for them.

Each game board section has a number of small holes formed therein as shown at 18 and the upper and lower surfaces of these game board sections can be covered with paper or the like as shown at 19, this covering material being provided with groups of dots 20 indicating the location of the holes thereunder. Within each hole is placed a slip of paper bearing a number or other character, or a name or any other data used in playing the game.

In practice the game board is inverted so that plate 1 is lowermost. Plate 8 is unlocked and removed and board sections 16 are placed on the upper surface of the inverted plate 1 and shifted laterally so as to engage the flanges 15.

of the baffles. Thereafter the central space surrounded by those board sections engaging the baffles is filled with additional board sections, plate 8 is placed in position and locked, and the board placed in playing position with plate 1 5 uppermost.

When playing the game any suitable device 10 is used by the players for punching from the board sections the pieces of paper or the like on which the data is displayed. The players 15 take turns and after all of the board sections have been punched, the numbers on the slips accumulated by each player are totalled, the player receiving the greatest total being the 20 winner of the game.

Should the game result in a tie, the plate 8 could be unlocked and removed, one or more additional board sections substituted for a like 25 number of used ones, and the game continued.

Should it be desired to reduce the size of the 30 playing area, some of the board sections could be removed and unperforated sections could be substituted therefor.

It will be noted that after the plate 8 has 35 been fastened in position, it becomes impossible to remove any one of the board sections because each of said sections is longer and wider than the opening through which it is exposed. Furthermore only those sections can be used which are adapted to receive the baffles 15. Obviously by changing the shape of the baffles and the corresponding grooves of the board sections, the 40 re-building of the game board can be controlled to a certain extent.

What is claimed is:
A game board including a top plate, said plate

having downturned flanges forming side walls and an end wall, a bottom plate insertible between the flanges, means for detachably securing the bottom plate against movement relative to the flanges, baffles secured to the top plate 5 and spaced inwardly from the flanges, each of said baffles including flanges disposed in a plane midway between the plates, a plurality of game board sections each having a groove extending therearound midway between opposed faces of 10 the sections, all of the grooves being proportioned to receive the flanges of the baffles, each game board section having a plurality of openings therein, game elements within the openings, and sheets secured to opposed faces of the sections and adapted to be perforated, said sheets normally concealing the openings and the game elements therein, certain of the game board sections being in engagement with the flanges of the baffles and additional game board elements 20 being fitted snugly thereagainst and against each other whereby the area defined by the baffles is completely filled with said game board sections, any one of said sections being reversible and replaceable for engagement with the flange 25 of one of the baffles, the said game board sections being held by and between the plates when the bottom plate is fastened to the top plate, there being a plurality of openings in the two plates, one opening in each plate being provided 30 for each game board section and proportioned to expose all portions of the adjacent surface of said sections except the margins thereof.
